United States Patent Office

Des. 197,258
Patented Dec. 31, 1963

197,258

OVERHEAD PROJECTOR

Samuel M. Highberger, Birmingham, Mich., assignor to
Minnesota Mining and Manufacturing Company,
St. Paul, Minn., a corporation of Delaware

Filed May 28, 1963, Ser. No. 75,106

Term of patent 14 years

(Cl. D61—1)

FIG. 1

FIG. 2

FIG. 3

FIG. 1 is a top front perspective view of an overhead projector, showing my new design;

FIG. 2 is a bottom rear perspective view thereof; and

FIG. 3 is an enlarged top plan view thereof.

The essential features of my design are shown in full lines.

I claim:

The ornamental design for an overhead projector, substantially as shown and described.
